UNITED STATES PATENT OFFICE.

ALFRED DWIGHT, OF AGAWAM, MASSACHUSETTS.

DESIGN FOR A PRINTER'S BODKIN.

UNITED STATES PATENT OFFICE.

ALFRED DWIGHT, OF AGAWAM, MASSACHUSETTS.

DESIGN FOR A PRINTER'S BODKIN.

SPECIFICATION forming part of Design No. 16,880, dated August 31, 1886.

Application filed July 22, 1886. Serial No. 208,808. Term of patent 3½ years.

To all whom it may concern:

Be it known that I, ALFRED DWIGHT, a citizen of the United States, residing at Agawam, in the county of Hampden and Commonwealth of Massachusetts, have invented and produced a new and original Design for Printer's Bodkin, of which the following is a specification, reference being had to the accompanying photographic illustration, forming part thereof.

In the photograph, *a* indicates the pointed portion of a printer's bodkin, and *b* indicates the shank or handle portion thereof. So far as I am aware, this shank or handle portion has heretofore been made cylindrical, or substantially so, in cross-section. In my new design this shank or handle portion is elliptical, or substantially so, in cross-section, the parallel sides having an equidistant outline from end to end, and terminates at the end next the

point in a square-cut vertical wall, and these constitute the leading feature of my design. The pointed portion or the shank or handle portion, or both, may be made of a different size and length from that I have shown without departing from the essence of my design. 25

I claim—

The design for a printer's bodkin herein shown and described, the same consisting of the point *a* and the shank or handle *b*, said shank or handle being substantially elliptical in cross-section, the parallel sides having an equidistant outline from end to end, and terminating at the end next the point in a square-cut vertical wall. 30 35

ALFRED DWIGHT.
